Fred. Ryan Inventor

By Samuel Herrick,
Attorney

UNITED STATES PATENT OFFICE.

FREDERICK RYAN, OF SAN ANTONIO, TEXAS.

CIRCUIT CLOSER FOR ALARMS.

Application filed February 27, 1923. Serial No. 621,500.

To all whom it may concern:

Be it known that FREDERICK RYAN, a citizen of the United States, residing at San Antonio, in the county of Bexar and State 5 of Texas, has invented certain new and useful Improvements in Circuit Closers for Alarms, of which the following is a specification.

This invention relates to an electric switch 10 and more particularly to a device adapted to be actuated upon the operation of another member instead of being actuated directly by hand.

Switches of the character described have 15 particular utility as automatic circuit closers in connection with burglar and thief alarms, whether upon residences, chicken houses, garages or otherwise, though their utility is not limited to that particular field.

20 In the accompanying drawing:

Fig. 1 is a vertical sectional view of a circuit closing device constructed in accordance with the invention;

Fig. 2 is a plan view of the inner member thereof; and

Fig. 3 is a sectional view illustrating the application of the device to a door.

Like numerals designate corresponding parts in all of the figures of the drawing.

The device of the present invention comprises an outer member consisting of a cylinder 5 having an outer end 6 and an inner end 7. A block of fiber or other insulating material, indicated at 8, is slidably mounted in this shell and is normally pressed outwardly within the shell by means of a spring 9. The inner end of this spring is preferably soldered at 10 to the inner edge 7 of this shell and the outer end of the spring bears against the inner end of the block of insulating material 8. A neck extension 11 formed upon the block 8 projects through an opening 12 formed in the head 6. The shell 5 is of metal and is adapted to have one of the conducting wires 13 of the circuit soldered thereto. The other wire of the circuit, indicated at 14, extends through an axial opening 15 formed in the block 8 and this axial opening communicates, at the juncture of the neck extension 11 with the body of the block 8, with a lateral opening 16 through which the wire 14 extends to the outer surface of the neck extension where 55 it is bent to form a coil 17 which surrounds

the neck extension at the base of said neck extension. Thus when the block 8 is pressed outward by the spring 9, the coil 17 is brought into contact with the metallic head 6 of shell 5 and the circuit is completed 60 through the shell and back to the conductor 13. It is manifest that whenever the extension 11 is pressed inwardly to move the coil 17 away from the head 6, the circuit will be broken. This may be effected 65 in varying ways. One example of the use of the device is given in Fig. 3 where the shell 5 has been inserted in an opening formed in a door jamb 18 and in such position that a door 19 hinged to said jamb 70 at 20 will contact with the extension 11 to thrust it inwardly whenever the door is closed. Thus if an unauthorized person attempts to open the door, which may be the door of a chicken house, garage, residence or any other place to be protected, the circuit will be completed and an alarm 75 may be sounded in a well known way.

It is to be understood that the invention is not limited to the precise construction set 80 forth but that it includes within its purview whatever changes fairly come within either the terms or the spirit of the appended claims.

Having described my invention what I 85 claim is:

1. A device of the character described comprising a casing of conductive material, a non-conductive block therein having a neck extension extending through an end 90 of said shell, means tending to press the block of insulating material toward the end of the shell and a conducting wire extending through the block and terminating in a coil which surrounds the neck extension at its 95 juncture with said block.

2. A device of the character described comprising an enclosing cylindrical shell having inner and outer ends, a block of insulating material slidable within the shell, 100 a spring bearing between the inner end of the shell and said block of insulating material and tending to thrust said block of insulating material outwardly, said shell being of conductive material, a conductor 105 attached to said shell, a neck extension upon the block and projecting through an end of said shell and a conducting wire extending axially through the insulating block to the juncture of the neck extension with said 110

block and then passing axially through said neck extension to the outer surface thereof and being formed into a coil about said neck extension, the insulation of the wire being removed at the point where it is coiled about said neck extension to thereby permit of electrical contact being made between said coiled part of the wire and the head of the cylindrical casing when the insulated block

is forced outwardly under the influence of 10 said spring.

In testimony whereof he affixes his signature in the presence of two witnesses.

FREDERICK RYAN.
